C. P. ASTROM.
HOT METAL LADLE CAR.
APPLICATION FILED DEC. 1, 1919.

1,347,984.

Patented July 27, 1920.

Attorney

UNITED STATES PATENT OFFICE.

CARL P. ASTROM, OF EAST ORANGE, NEW JERSEY, ASSIGNOR TO M. H. TREADWELL COMPANY, OF NEW YORK, N. Y., A CORPORATION OF NEW YORK.

HOT-METAL LADLE-CAR.

1,347,984.

Specification of Letters Patent. Patented July 27, 1920.

Application filed December 1, 1919. Serial No. 341,780.

To all whom it may concern:

Be it known that I, CARL P. ASTROM, a citizen of the United States, and resident of East Orange, in the county of Essex and

5 State of New Jersey, have invented certain new and useful Improvements in Hot-Metal Ladle-Cars, of which the following is a specification.

This invention relates to the handling of 10 hot metal such as molten iron and steel and the object of the invention is to retain so far as possible the heat of the metal during the transfer thereof from the furnace to the casting pit, or other point. In such transfer 15 the hot metal is usually transported in an open pouring ladle.

The invention provides a ladle or car body 20 with a heat retaining cover secured in position in such a way as to remain in position during the pouring and without interfering with such pouring operation, or other uses where retention of heat is not desired.

The invention will be more fully understood by reference to the accompanying 25 drawing forming a part of this specification, wherein Figure 1 is an end view of a car showing the ladle in position thereon and equipped with a heat retaining cover, the ladle and a part of the cover being indicated 30 as broken away and appearing in section.

Fig. 2 is a broken front view of the ladle and its cover.

The hot metal car which is designated 5 may be of any usual or preferred construction and is shown as constructed to support the ladle 6 which is provided with pouring trunnions 7 and 8 journaled in the bearings 9 and 10 provided on the car body. In addition, this ladle is shown as provided with the 40 usual centrally disposed trunnions 11 for the engagement of the crane hooks, or other lifting device.

12 designates the cover for the ladle which is shown as provided with a heat retaining lining 13 and is furthermore shown 45 as cut away at its opposite edges at 14 in line with the pouring spouts 15 of the ladle. This cover is also shown provided with a suitable yoke or lifting device 16 by which 50 the same may be transported and applied to or removed from the ladle.

This removable cover is detachably secured in position closing the mouth of the ladle by fastenings comprising in the present instance coupling bolts 17 engaged be-

tween the flange portion 18 of the cover and the abutments or brackets 19 on the rim portion of the ladle. This construction provides a secure means for holding the cover in position on the ladle irrespective of the 60 tilted position of the ladle, and also gets the fastenings away from the heat. At the same time the cover may be readily released by loosening and detaching the said coupling 65 bolts.

The notch or notches 14 in the rim of the cover which register with the pouring spout or spouts provide an easy entrance or exit for the molten metal so that the cover may remain in place both when the ladle is being 70 charged and discharged. In Fig. 1 I have indicated how with this construction the ladle may be charged directly from the spout 20 of the furnace, with the cover in position.

21 is a wedge block or chock to support the frame bolster 24 during dumping so as to maintain a short pour on a fixed trunnion axis, to runner 22. 23 is a support for chock 21, the latter being operated by levers 80 25. 26 is the loop for the crane chain in dumping.

When not desired for hot metal, as for cinder, etc., the cover can be removed making an ordinary open ladle, or car body and 85 also when cleaning or relining is desired.

The cover consists of a continuous ring frame with the opposite recessed portions at 14, which permit expansion and contraction without loosening the brick lining. 90 This ring has an inner flange which supports the bricks, and also fits the top of the ladle, and the bricks are protected from rough handling of the cover by the top metal plate secured to the ring outside the 95 bricks.

The construction disclosed materially assists in retaining the heat of the metal without interfering with the pouring or the charging of the ladle, and the cover can 100 easily be removed for other purposes.

What I claim is:

1. In a hot metal car, a ladle for hot metal and a cover composed of a ring having a pouring recess, a refractory lining supported 105 by the ring, and a plate top, the ring recess permitting expansion and contraction with temperature changes without loosening the lining.

2. The combination with a ladle for hot 110

metal provided with a pouring spout, of a cover comprising an arcuate metallic member covered on its underside with a heat resisting body, said cover being provided with 5 a notch in the rim thereof in line with the pouring spout, and metallic means for holding said heat resisting body in place.

3. The combination with a ladle for hot metal provided with a pouring spout, of an 10 inverted dish shaped metallic cover formed with a flange around the edge thereof and a notch in the rim in line with the pouring spout, a refractory lining in the dish, means for holding said lining in place and means 15 for detachably securing said flange to the ladle.

4. The combination with a ladle for hot metal provided with a pouring spout, of an 20 inverted dish shaped cover formed with a flange around the edge thereof and a notch in the rim in line with the pouring spout, means for detachably securing said flange to the ladle and means for attaching a lifting 25 means to said cover.

5. The combination with a ladle for hot metal provided with a pouring spout, of an inverted dish shaped cover formed with a notch in the rim in line with the pouring spout, said ladle being provided with trunnions relatively near the top of the spout to 30 enable a "short pour" to be made and means for holding the cover in place during the pouring.

6. The combination with a ladle for hot metal provided with a plurality of pouring 35 spouts, of an inverted dish shaped cover formed with a plurality of notches in the rim, each one in line with a pouring spout, said ladle being provided with a plurality of trunnions each relatively near the top of 40 the spout and arranged in pairs to enable a "short pour" to be made from any of the spouts and means for holding the cover in place during the pouring.

Signed at New York city in the county of 45 New York and State of New York this 26 day of November A. D. 1919.

CARL P. ASTROM.
